GIRAFFE FIGURE SEAT FOR PLAY-GROUND EQUIPMENT

Robert S. Wormser, Hillsdale, Mich., assignor to Game Time, Inc., Litchfield, Mich.

Filed Feb. 9, 1970, Ser. No. 21,350

Term of patent 14 years

Int. Cl. D21—04

U.S. Cl. D34—15

FIG. 1

FIG. 2

FIG. 1 is a side elevational view of giraffe figure seat for playground equipment illustrating my new design as taken from the right side thereof, the left side being substantially identical thereto.

FIG. 2 is a front side, elevational view as taken from the right of FIG. 1.

FIG. 3 is a rear elevational view as taken from the left of FIG. 1, and

FIG. 4 is a top plan view of my new design.

I claim:

The ornamental design for giraffe figure seat for playground equipment, substantially as shown and described.
